GYROSCOPIC STABILIZER

James R. Kuiper, Grand Rapids, Mich., assignor to R. C. Allen Business Machines, Inc., Grand Rapids, Mich., a corporation of Michigan

Application October 10, 1957, Serial No. 689,355

10 Claims. (Cl. 74—5.22)

This invention relates to gyroscopic stabilizers, and more particularly to a stabilizer adapted to be clamped to a hand-held sighting device, such as binoculars, sextants, cameras and the like for the purpose of eliminating tremors, vibrations or other unsteadiness which could render the sighting device unusable.

Hand-held sighting devices, and especially high powered sighting devices, such as binoculars, are difficult to hold steady enough for securing a sharp image of the object under observation within the line of sight since vibrations of the device resulting from hand tremor or other vibration blurs the image of the observed object sufficiently to destroy its clarity and reduce the effectiveness of the device. Heretofore, gyroscopic stabilizers have been developed for sighting devices, but have been relatively bulky and heavy.

The gyroscopic stabilizer of the present invention is constructed so that it may be easily clamped to a sighting device such as binoculars in such a manner that the center of gravity of the binoculars is directly over the stabilizer, wherein the stabilizer will not interfere with the facial outline of the mouth and the nose of the user. The stabilizer includes a tubular casing having a pair of gyro frames rotatably supported within the casing. The gyro frames have their axes of rotation perpendicular to each other and located in a common diametrical plane of the casing normal to the sighting axis of the sighting device. A rotor is rotatably supported in each frame with its axis of rotation perpendicular to the axis of rotation of its frame. The axes of rotation of the frames are inclined so that they extend upwardly and outwardly, thereby saving weight and space in construction and defining a compact stabilizer. While the rotors may be driven by an air stream, they are illustrated herein as being driven by electric motors.

Accordingly, it is an object of this invention to provide a gyroscopic stabilizer adapted to be attached to sighting devices, and including a pair of gyros mounted in a casing to provide a relatively compact unit.

Another object of this invention resides in the provision of a gyroscopic stabilizer for sighting devices including a pair of gyros mounted within a casing, wherein the gyros are mounted at an incline in order to provide a compact unit and thereby enabling a greater rotor diameter to be employed with a given case size, thus permitting a greater rotor inertia to rotor weight ratio thereby increasing the capacity of the stabilizer.

Still another object of this invention is in the provision of a gyroscopic stabilizer adapted to be attached to a sighting device such as hand-held binoculars, wherein the axis of the casing of the stabilizer is positioned perpendicular to the axis of the binoculars, wherein the stabilizer may be clamped beneath the center of gravity of the binoculars without interfering with the facial outline of the mouth and nose of the user.

A further object of this invention is to provide a gyroscopic stabilizer for sighting devices having a pair

2

of gyros mounted within a casing, wherein the vectorial summation of the stabilizing forces of the gyros are maximum in both the horizontal plane and the vertical plane.

5 A still further object of this invention resides in the provision of a gyroscopic stabilizer for use on sighting devices having a pair of gyros mounted within a casing, wherein the axes of rotation of the rotors of each gyro are parallel to each other and the rotors are driven in opposite directions to avoid undesirable reaction torques on the casing while maneuvering the gyroscopic stabilizer.

Other objects, features, and advantages of the invention will be apparent from the following detailed description, taken in conjunction with the accompanying sheets of drawings, wherein like reference numerals refer to like parts, in which:

Fig. 1 is a side elevational view of a binoculars having mounted thereon the gyroscopic stabilizer according to the present invention;

Fig. 2 is an end elevational view of the arrangement of Fig. 1;

Fig. 3 is a greatly enlarged fragmentary view of the gyroscopic stabilizer according to the invention illustrating the tubular casing with portions broken away to show underlying parts and the arrangement of the gyros within the casing as they are mounted therein;

Fig. 4 is a fragmentary and greatly enlarged detail view of the mounting of a gyro frame at the upper end thereof;

Fig. 5 is a fragmentary and greatly enlarged detail view of the mounting of a gyro frame at the lower end thereof;

Fig. 6 is a sectional view, taken substantially along the line 5—5 of Fig. 3;

Fig. 7 is a sectional view taken substantially along line 6—6 of Fig. 3, showing some parts in elevation;

Fig. 8 is a diagrammatic view of an electric circuit for operating the motors which drive the gyros;

Fig. 9 is a fragmentary section taken through the stabilizer housing showing the terminal board in plan view; and

Fig. 10 is an enlarged fragmentary view showing how the terminal board is secured to the stabilizer housing and taken along lines 10—10 of Fig. 9.

Referring now to the drawings, and especially to Figs. 1 and 2, the gyroscopic stabilizer of the present invention, generally designated by the numeral 10, is shown mounted on a binoculars 11, wherein the stabilizer 10 is mounted beneath the center of gravity of the binoculars 11 in such a position so that the axis of the stabilizer is positioned perpendicular to the sighting axis of the binoculars which gives the line of sight from eye E to object B. By arranging the stabilizer 10 relative to the binoculars 11 in this fashion, it will be appreciated that there is no interference with the facial outline of the user on the part of the stabilizer.

The gyroscopic stabilizer 10 includes a tubular casing 12 having secured centrally thereof an upwardly extending supporting bar 13. The supporting bar is arcuately bent at its upper end and has attached thereto a clamp 14 which includes a pair of clamping members 15 at the lower end adjustable by manipulation of a control knob 16 at the upper end, wherein the clamping members are adapted to engage a center rod 17 of the binoculars as illustrated. Although the gyroscopic stabilizer of the present invention is shown only as mounted on binoculars, it will be appreciated that the stabilizer may be utilized with any other type of sighting device or wherever it is needed to reduce or eliminate vibration of a device for effective operation thereof. It would

only be necessary to improvise the mounting arrangement in order to adapt the stabilizer of the present invention for any other type of device.

The casing 12 of the stabilizer has mounted therein a pair of spaced apart gyros 18 and 19 which comprise generally gyro frames 20 and 21 and gyro rotors 22 and 23, respectively. The gyro frames are rotatably mounted in the casing along inclined axes of rotation which extend perpendicular to each other and are located in a common diametral plane of the casing 12 normal to the sighting axis of the binoculars 11. Inclining of the gyro frames permits a greater rotor diameter to be employed within a given casing size, thus permitting a greater rotor inertia to rotor weight ratio. Hence, a compact stabilizer unit having a greater capacity can be constructed in any given casing size. Preferably, the axes of rotation of the gyro frames are inclined 45° from a radial plane extending through the casing 12, wherein the axes extend upwardly and outwardly from the bottom of the casing.

The gyro frames are supported within the casing by means of mounting rings 24 and 25 secured to opposite ends of the casing and a mounting block 26 arranged near the center of the casing and at the bottom thereof. The mounting block 26 includes oppositely inclined faces 27 and 28, each of which has provided therein a cup shaped opening or blind bore 29, Fig. 5. A bearing insert 30 is held in place in the opening and engages a ball bearing 31. The ball bearing 31, in turn, engages a ball bearing race 32 which is mounted in one end of each gyro frame.

The gyro frames 20 and 21 are identical and as seen in Figs. 6 and 7 are substantially octagonal in shape. Referring particularly to Fig. 7 which illustrates the gyro frame 20, it is seen that each frame includes parallel opposed upper and lower bars 33 and 34, respectively, parallel opposed side bars 35 and 36, upper oppositely inclined bars 37 and 38, and lower inclined bars 39 and 40. It is the lower bar 34 which supports the ball race 32 for engaging the ball bearing 31. The upper bar 33 similarly supports a ball bearing race 41, Fig. 4, which engages a large ball bearing 42. The ball bearing 42, in turn, engages a socket 43 formed in an adjusting screw 44 threadedly received in an inclined projection 45 carried by the mounting ring 24. This inclined projection parallels the inclined face 27 on the mounting block 26. Similarly, the frame 21 is mounted at its upper end on an inclined projection 46 of the mounting ring 25. The locking screw 47 locks the adjusting screw 44 in position and is also threadedly received in the projection 45. Thus, the gyro frames may be adjustable mounted within the casing during assembly in order to give the proper bearing fit or proper rotational operation of the frames along their axes of rotation without necessitating manufacturing of the various parts of the stabilizer to extremely close tolerances. The mounting block 26 and the supporting ring projections 45 and 46 are arranged in direct alignment with a common diametral plane, and the mounting block is located centrally of the casing 12. Similarly, the cup shaped openings and bearing inserts of the oppositely inclined faces on the mounting block 26 are aligned along the same diametral plane as the projections 45 and 46, whereby the axes of rotation of the gyro frames are located in a common diametral plane of the casing 12. This diametral plane is perpendicular to the sighting axis of the binoculars or sighting instrument.

Each gyro rotor is electrically driven and actually constitutes the cage rotor of an induction motor, wherein the inner member of the motor is the stator and is fixed between the side bars 35 and 36 of the gyro frame. The spin axis or axis of rotation of each rotor parallels the sight axis of the sighting instrument.

The wires leading from the windings of each motor are extended to a horizontal common terminal board 48

of insulating material carried within the casing and secured to the mounting block 26, Figs. 3, 9, and 10. From the terminal board, cables may extend through a hollow or bore 49 formed in the center of the mounting block 26 through a fitting 50 to a source of electrical energy. The terminal board 48, as seen in Fig. 9, includes a transversely extending center section 51 with offset wing sections 52 and 53 extending from opposite ends thereof. A hold down plate 54 is arranged over the central part of section 51 and has upstanding flanges at each end which may support a condenser 55 thereon if one is to be used. The plate 54 and the terminal board 48 are provided with aligned holes for receiving mounting pins 56 which are suitably anchored in the mounting block 26, Fig. 10, and conventional snap lock rings 57 are received by the pins over the plate 54 to lock the plate and terminal board to the mounting block. Spacers 58 space the terminal board slightly above the mounting block. Terminals 59, three in this instance, or whatever number is necessary, are mounted on the terminal board to make the necessary connections between the wires leading to the motors and power source. Further suitable apertures 60 and 61 are provided in the terminal board for the purpose of maintaining the wires in a certain position within the casing and making connections between the terminals and to the wires leading to the power source.

The motors of the gyros 18 and 19 have their windings connected in parallel in a manner similar to that shown in Fig. 8 so that the rotors will rotate in opposite directions. By rotating the rotors in opposite directions, undesirable reaction torques are eliminated which would arise while maneuvering the stabilizer and binoculars, which reaction torques would occur if the rotors rotate in the same direction.

A spring 62 is secured at one end to the frame 20 and at the other end to the casing 12, Figs. 6 and 7, to define a spring restraint between the frame and casing for maintaining the axis of each rotor parallel to the sight axis in its undeflected position. Similarly, a like spring restraint means will be provided between the frame 21 of the gyro 19 and the casing 12.

The opposite open ends of the casing 12 may be closed by covers 63 and 64, Fig. 3; and to increase the efficiency of the unit, the case may be filled with helium or any other light gas and hermetically sealed to decrease rotational friction of the rotors.

Since the windings of the rotors of each gyro may be connected to the common terminal board 48, the electrical arrangement is more compactly constructed and provides a single point to bring in electrical energy for driving the rotors. Similarly, if an air stream is used as a driving means for the rotors, this being a common practice in the art, the rotors may be driven from a central port.

When considering rotation of the casing about an axis perpendicular to both the rotational axis of one rotor and the rotational axis of its frame, the gyro action is such that the torque tending to rotate the casing produces a precession of the frame about its axis which precession produces a torque on the casing in the opposite direction. As the restraining spring limits the precession rate of the frame, it also limits the torque opposing the rotation of the case, allowing case rotation. Thus, a given rotation rate of the casing will be balanced by a given torque of the gyro applied against the restraining spring. Therefore, it will be seen that any change of rate of rotation of the casing will be balanced by precession of the gyro and any precession of the gyro will be balanced by a change of rate of rotation of the casing. This same reasoning applies to the other gyro when considering rotation of the case about an axis perpendicular to both the rotational axis of its rotor and the rotational axis of its frame. Thus, it is apparent that any rotations of the casing constituted by vectorial rotational quantities in the

two axes just considered, will likewise cause precessions of the gyro frames with resulting stabilizing action, each gyro deflection being proportional to the vectorial rotation rate in its stabilizing axis. In effect, all change of rate of rotations of the casing in all axes other than the sight axis, including tremors, vibrations, and other unsteadiness, will be stabilized within the limits of the gyro capabilities. Thus, object B will be sharp and neither blurred nor hazy. Because of the inclined arrangement of the gyro frames as illustrated, the vectorial summation of stabilizing forces of the gyros is maximum in both the horizontal plane and the vertical plane.

It will be understood that modifications and variations may be effected without departing from the scope of the novel concepts of the present invention.

The invention is hereby claimed as follows:

1. In combination with a sighting device, a tubular casing, a support member secured to said casing having means thereon for attaching it to said sighting device to maintain said casing with its axis perpendicular to the sighting axis of said device, a first gyro frame within said casing, means for supporting said frame within said casing for rotation about an inclined axis, a rotor rotatively supported by said frame for rotation about an axis perpendicular to the axis of rotation of the frame, a second gyro frame within said casing, means for supporting said second frame within said casing for rotation about an inclined axis, a rotor rotatively supported by said second frame for rotation about an axis perpendicular to the axis of rotation of said second frame, the spin axes of said rotors extending parallel to each other and to the sighting axis, the plane extending through the rotor axes being spaced below a parallel plane containing the sighting axis and spring restraint means for each gyro frame.

2. In combination with a sighting device, a tubular casing, a support member secured to said casing having means thereon for attaching it to said sighting device to maintain said casing with its axis perpendicular to the sighting axis of said device, a first gyro frame within said casing, means for supporting said frame within said casing for rotation about an inclined axis, a rotor rotatively supported by said frame for rotation about an axis perpendicular to the axis of rotation of the frame, a second gyro frame within said casing, means for supporting said second frame within said casing for rotation about an axis perpendicular to the axis of rotation of said first frame, a rotor rotatively supported by said second frame for rotation about an axis perpendicular to the axis of rotation of said second frame, the spin axes of said rotors extending parallel to each other and to the sighting axis, the plane extending through the rotor axes being spaced below a parallel plane containing the sighting axis and spring restraint means for each gyro frame.

3. In combination with a sighting device, a tubular casing, a support member secured to said casing having means thereon for attaching it to said sighting device to maintain said casing with its axis perpendicular to the sighting axis of said device, a first gyro frame within said casing, means for supporting said frame within said casing for rotation about an inclined axis, a rotor rotatively supported by said frame for rotation about an axis perpendicular to the axis of rotation of the frame, a second gyro frame within said casing, means for supporting said second frame within said casing for rotation about an inclined axis, the axes of rotation of said frames extending upwardly and outwardly, and a rotor rotatively supported by said second frame for rotation about an axis perpendicular to the axis of rotation of said second frame, the spin axes of said rotors extending parallel to each other and to the sighting axis, the plane extending through the rotor axes being spaced below a parallel plane containing the sighting axis.

4. In combination with a sighting device, a tubular casing, a support member secured to said casing having means thereon for attaching it to said sighting device to

5 maintain said casing with its axis perpendicular to the sighting axis of said device, a first gyro frame within said casing, means for supporting said frame within said casing for rotation about an inclined axis, a rotor rotatively supported by said frame for rotation about an axis perpendicular to the axis of rotation of the frame, a second gyro frame within said casing, means for supporting said second frame within said casing for rotation about an inclined axis, a rotor rotatively supported by said second frame for rotation about an axis perpendicular to the axis of rotation of said second frame, the spin axes of said rotors extending parallel to each other and to the sighting axis, the axes of rotation of said frames extending upwardly and outwardly, the plane extending through the 10 rotor axes being spaced below the parallel plane containing the sighting axis, spring restraint means for each gyro frame, and driving means for rotating said rotors.

5. In combination with a sighting device, a tubular casing, a support member secured to said casing having 20 means thereon for attaching it to said sighting device to maintain said casing with its axis perpendicular to the sighting axis of said device, a first gyro frame within said casing, means for supporting said frame within said casing for rotation about an inclined axis, a rotor rotatively supported by said frame for rotation about an axis perpendicular to the axis of rotation of the frame, a second gyro frame within said casing, means for supporting said second frame within said casing for rotation about an inclined axis, a rotor rotatively supported by said second frame for rotation about an axis perpendicular to the axis of rotation of said second frame, the spin axes of said rotors extending parallel to each other and to the sighting axis, the plane extending through the rotor axes being 25 spaced below a parallel plane containing the sighting axis, 30 spring restraint means for each gyro frame, and driving means for rotating said rotors in opposite directions.

6. In combination with a sighting device, a tubular casing, a support member secured to said casing having means thereon for attaching it to said sighting device to 40 maintain said casing with its axis perpendicular to the sighting axis of said device, a first gyro frame within said casing, means for supporting said frame within said casing for rotation about an inclined axis, a rotor rotatively supported by said frame for rotation about an axis perpendicular to the axis of rotation of the frame, a second gyro frame within said casing, means for supporting said second frame within said casing for rotation about an axis perpendicular to the axis of rotation of said first frame, a rotor rotatively supported by said second frame for rotation about an axis perpendicular to the axis of rotation of said second frame, the spin axes of said rotors extending parallel to each other and to the sighting axis, the plane extending through the rotor axes being spaced below a 45 parallel plane containing the sighting axis, spring restraint means for each gyro frame, and driving means for rotating said rotors in opposite directions.

7. A gyroscopic stabilizer adapted to be mounted on a sighting device comprising, a tubular casing arranged perpendicular to the sighting axis, a first gyro frame within said casing, means for supporting said frame within said casing for rotation about an inclined axis, a rotor rotatively supported by said frame for rotation about an axis perpendicular to the axis of rotation of the frame, a second gyro frame within said casing, means for supporting said second frame within said casing for rotation about an axis perpendicular to the axis of rotation of said first frame, the axes of rotation of said frames extending upwardly and outwardly, a rotor rotatively supported by said second frame for rotation about an axis perpendicular to the axis of rotation of said second frame, the plane extending through the rotor axes being spaced below a parallel plane containing the sighting axis, and spring restraint means between each frame and the casing for maintaining the axis of each rotor parallel to the sighting axis in its undeflected position.

8. In combination with a sighting device, a gyroscopic stabilizer comprising, a tubular casing having a clamping device for attaching it to the sighting device to maintain the axis of said casing perpendicular to the sighting axis of said sighting device, a pair of gyro frames rotatably supported within said casing having their axes of rotation extending upwardly and outwardly and perpendicular to each other and located in a common diametral plane of the casing normal to the sighting axis, and a rotor rotatably supported by each frame, the plane extending through the rotor axes being spaced below a parallel plane containing the sighting axis, each rotor having its axis of rotation perpendicular to the axis of rotation of its frame and said common diametral plane.

9. In combination with a sighting device, a gyroscopic stabilizer comprising, a tubular casing having a clamping device for attaching it to the sighting device to maintain the axis of said casing perpendicular to the sighting axis of said sighting device, a pair of gyro frames rotatably supported within said casing having their axes of rotation extending upwardly and outwardly and perpendicular to each other and located in a common diametral plane of the casing normal to the sighting axis, a rotor rotatably supported by each frame, the plane extending through the rotor axes being spaced below a parallel plane containing the sighting axis, each rotor having its axis of rotation perpendicular to the axis of rotation of its frame and said common diametral plane, and a spring restraint between

each frame and the casing to maintain the axis of each rotor parallel to the sighting axis in its undeflected position.

10. In combination with a sighting device, a gyroscopic stabilizer comprising, a tubular casing having a clamping device for attaching it to the sighting device to maintain the axis of said casing perpendicular to the sighting axis of said sighting device, a pair of gyro frames rotatably supported within said casing having their axes of rotation extending upwardly and outwardly and perpendicular to each other and located in a common diametral plane of the casing normal to the sighting axis, a rotor rotatably supported by each frame, the plane extending through the rotor axes being spaced below a parallel plane containing the sighting axis, each rotor having its axis of rotation perpendicular to the axis of rotation of its frame and said common diametral plane, a spring restraint between each frame and the casing to maintain the axis of each rotor parallel to the sighting axis in its undeflected position, and means for driving said rotors in opposite directions.
